(57) **CLAIM**

The ornamental design for an electronic device, as shown and described.

DESCRIPTION

FIG. 1 is a top, front, right-side perspective view of an electronic device;

FIG. 2 is a top, front, left-side perspective view thereof;

FIG. 3 is a bottom, back, right-side view thereof;

FIG. 4 is a bottom, back, left-side view thereof;

FIG. 5 is a front view thereof;

FIG. 6 is a back view thereof;

FIG. 7 is a right-side view thereof;

FIG. 8 is a left-side view thereof;

FIG. 9 is a top view thereof;

FIG. 10 is a bottom view thereof; and,

FIG. 11 is a top, front, left-side perspective view thereof including disclaimed environment of the electronic device. The broken lines depict portions of the article and form no part of the claimed design. The additional broken lines in FIG. 11 show environment and form no part of the claimed design.
